UNITED STATES PATENT OFFICE.

MEYER M. KANE, OF CHICAGO, ILLINOIS.

IRONING APPARATUS.

1,111,467.

Specification of Letters Patent. Patented Sept. 22, 1914.

Application filed January 6, 1914. Serial No. 810,632.

To all whom it may concern:

Be it known that I, MEYER M. KANE, a citizen of the United States, residing at Chicago, in the county of Cook and State 5 of Illinois, have invented certain new and useful Improvements in Ironing Apparatus; and I do hereby declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to new and useful improvements in ironing apparatus and the object in view is to produce a simple and efficient apparatus of this nature adapted to relieve the person ironing of the strain and 20 weight incident to the iron as it is moved back and forth over the articles being ironed.

The present invention comprises various details of construction, combinations and 25 arrangements of parts which will be hereinafter fully described, shown in the accompanying drawings and then specifically defined in the appended claims.

I illustrate my invention in the accompanying drawings, in which:

Figure 1 is a side elevation of an ironing apparatus embodying the features of my invention. Fig. 2 is a top plan view. Fig. 3 is a sectional view on line 3-3 of Fig. 2, 35 and Fig. 4 is a detail sectional view on line 4-4 of Fig. 1.

Reference now being had to the details of the drawings by letter, A designates a bench upon which a plate B is fastened and 40 C, C designate standards suitably mounted upon said plate and supporting at their upper ends cross-pieces D from which rise rods E.

F is a horizontally disposed rod having 45 extensible sections F² telescoping in the ends and adapted to be held in adjusted positions, said sections having eyes at their ends and through which said rods E pass. A head H is fastened to the upper end of 50 each rod and washers H' are mounted, one upon each rod E, and a coiled spring H²

bearing intermediate each cross-piece and one of said washers on which an end of the extensible rod rests are adapted to normally hold the horizontally disposed rod at its 55 highest upper limit.

A carriage, designated by letter L, has grooved pulleys L' therein which rest upon said horizontally disposed rod and depending from said carriage is an eye bolt N 60 fastened to the upper end of a spring O which is located within the shell Q, and is secured to the lower end thereof, the shell Q telescoping within a shell Q'. A set screw O' passes through an aperture in said 65 shell Q' and is adapted to hold the latter in an adjusted position. The iron, designated by letter P, has a handle P' and a bail-shaped member P² is fastened at its ends to the ends of said handle and is bent at R to 70 form a loop which telescopes within the lower end of the shell Q'. A pin R' passes through registering apertures in the shell Q' and engages said loop and forms a means of connection between the same and shell. 75

Pivotedly connected to said iron is a slotted bar S which is held in adjusted position upon the carriage T by means of the clamping plates T' having screws T² passing through apertures in the upper plate 80 through the slot in the bar S and engaging screw-threaded openings in the lower plate, these plates forming parts of the carriage T. A hook, designated by letter T³, is fastened to one of said clamping plates T' and engages underneath the bar M and co-operates with the under one of the plates T' which projects over the bar M to guide the clamping plate as the carriage, to which the plate is attached, is moved back and forth upon 85 the track W. Grooved pulleys T² are mounted between the walls of the carriage T and ride upon the horizontally disposed track W, which latter has angled portions near their ends telescoping within the sockets V, the vertical portions of said tracks which telescope being provided with rack teeth X which mesh with the teeth of the pinions Y. Said pinions Y are fixed to a shaft Z which is journaled in the bearings 90 Z' upon the bench, a suitable handle being 100 attached to one end of the shaft. Set screws,

designated by letter J, are mounted in said sockets and are adapted to hold the track in adjusted position. A bail-shaped member, designated by letter M, has apertures 5 M' in the ends thereof which are journaled upon said track, the latter being preferably of cylindrical shape, and a rod G is pivotally connected at its upper end to said bail-shaped member M and telescopes within the 10 tubular shell G' which is pivoted at G² to a lever G², which latter is pivotally mounted upon a pin G⁴ carried by the bracket members G⁵, said lever being adapted to be tilted by the foot of the operator. A spring I' is 15 fastened at one end to a part of the frame and its other end to the eye I² upon said bail-shaped member M and serves as a means for returning the bail and iron connected therewith to their normal position to elevate the iron from the work when the iron is not in use.

The operation of my invention will be readily understood and is as follows:—The article to be ironed is placed upon the 25 bench or an ironing board and the operator by stepping upon the lever may cause the bail-shaped member M to tilt and with it the carriage and, as the plate S is clamped to the carriage, said plate S will tilt down 30 and throw the iron toward the table. The iron may be further pressed down by the operator taking hold of the iron, the latter yielding by reason of the spring connections shown and the iron may be moved back and 35 forth over the ironing board, the carriage running upon the tracks, as will be readily understood. Through the medium of the adjusting means, it will be observed that the iron may be held at different elevations to 40 adapt the same to the work resting upon the bench.

What I claim to be new is:—

1. An ironing machine comprising a bench with standards thereon, a horizontally 45 disposed, spring-pressed rod supported upon said standards, a carriage with wheels movable upon said rod, an iron hanging yieldingly from said carriage, a rocking member, a track upon which the same is 50 mounted, connections between said iron and rocking member, and means for rocking said member, as set forth.

2. An ironing frame comprising standards, a horizontally disposed, spring-pressed 55 rod supported thereon, a carriage movable upon said rod, a yielding hanger suspended from said carriage, an iron secured to the hanger, a vertically adjustable track, a carriage movable upon the latter, a connection 60 between said carriage upon the track and said iron, and means for tilting said connection to press the iron against an article to be ironed, as set forth.

3. An ironing frame comprising standards, a horizontally disposed, spring-pressed 65 rod supported thereon, a carriage movable upon said rod, a yielding hanger suspended from said carriage, an iron secured to the hanger, a vertically adjustable track, a rocking bail-shaped member mounted upon said 70 track, means for rocking said member, a carriage movable upon the track, means secured to the carriage and engaging the iron and said bail-shaped member and serving to apply pressure to the iron as said bail-shaped member is rocked in one direction, 75 as set forth.

4. An ironing frame comprising standards, a horizontally disposed, spring-pressed rod supported thereon, a carriage movable 80 upon said rod, a yielding hanger suspended from said carriage, an iron secured to the hanger, a vertically adjustable track, a rocking bail-shaped member mounted upon said track, means for rocking said member, a carriage movable upon the track, a pivotal bar connected at one end to said iron and adjustably connected to the carriage upon said track, and means connected to the carriage and adapted to engage under said bail-shaped member, as set forth. 90

5. An ironing frame comprising standards, a horizontally disposed, spring-pressed rod supported thereon, a carriage movable 95 upon said rod, a yielding hanger suspended from said carriage, an iron secured to the hanger, a horizontally disposed track having vertical portions, sockets in which the latter are mounted, rack teeth upon said vertical portions of the track, a rotatable shaft, 100 pinion wheels fixed thereto and engaging the teeth of said shaft, means for holding the track in an adjusted position, a bail-shaped member pivotally mounted upon the track, a carriage upon the latter, a bar 105 pivotally connected at one end to the iron and adjustably mounted upon the carriage on said track, and means actuated by the bail-shaped member and co-operating with the bar which is pivoted to the iron for applying pressure to the latter, as set forth.

6. An ironing frame comprising standards, a horizontally disposed, spring-pressed rod supported thereon, a carriage movable 110 upon said rod, a yielding hanger suspended from said carriage, an iron secured to the hanger, a horizontally disposed track having vertical portions, sockets in which the latter are mounted, rack teeth upon said vertical portions of the track, a rotatable shaft, 115 pinion wheels fixed thereto and engaging the teeth of said shaft, means for holding the track in an adjusted position, a bail-shaped member pivotally mounted upon the track, a carriage upon the latter, a bar pivotally connected at one end to the iron and 120

adjustably mounted upon the carriage on
said track, and means actuated by the bail-
shaped member and coöperating with the
bar which is pivoted to the iron for apply-
5 ing pressure to the latter, and a pivoted
tread lever having connection with said
bail-shaped member, as set forth.

In testimony whereof I hereunto affix my
signature in presence of two witnesses.

MEYER M. KANE.
